UNITED STATES PATENT OFFICE.

FRANCIS M. ROSENFIELD, OF NEW YORK, N. Y., AND LOUIS E. SHAW, OF EAST ORANGE, NEW JERSEY, ASSIGNORS TO IMPORT SALES COMPANY, OF NEW YORK, N. Y., A CORPORATION OF NEW YORK.

ELECTRIC LAMP.

1,289,550.

Specification of Letters Patent. Patented Dec. 31, 1918.

Application filed March 7, 1918. Serial No. 220,941.

To all whom it may concern:

Be it known that we, FRANCIS M. ROSENFIELD, a citizen of the United States, and a resident of the city, county, and State of New York, and LOUIS E. SHAW, a citizen of the United States, and a resident of East Orange, Essex county, New Jersey, have invented an Improvement in Electric Lamps, of which the following is a specification.

10 Our invention relates to electric lamps of a character peculiarly adapted to being in part disassembled for the purpose of compact packing, but our improvements are not limited to this type of lamp, and may be 15 applied to many other types of electric lamps without substantial change. The drawings accompanying this specification, however, illustrate a type of lamp which might be termed a traveling lamp, wherein 20 the various parts of the lamp may be packed into the lamp housing, thus making a convenient and compact structure for transportation. It should be understood, however, 25 that these drawings are illustrative merely of one form that our invention may take and are not intended to show the only form in which our invention may be embodied.

In the drawings,

Figure 1 is a front view of our improved 30 lamp in an assembled condition;

Fig. 2 is a vertical, sectional view thereof;

Fig. 3 is a side view of the base of our improved lamp, the base being that used in the embodiment illustrated in Fig. 2;

35 Fig. 4 is a plan view of the base shown in Figs. 2 and 3;

Fig. 5 is a side view of the base shown in Figs. 2, 3 and 4, showing the base being used to attach the lamp to a table or other 40 suitable support;

Fig. 6 is a sectional view of a modified form of the base and standard;

Fig. 7 is a plan view thereof; and

45 Fig. 8 is a side view of the base illustrated in Figs. 6 and 7, showing the means for attaching said base to a table or other suitable support.

In the drawings, 1 illustrates a housing, which may be tubular, or of any other suitable shape, that illustrated being tubular. It is preferably made of brass or other suitable material and having an aperture 2 extending substantially the entire length of

the tube and throughout a suitable circumferential distance.

The tubular housing 1 is closed at each end by means of caps 3 and 4. Cap 4 is preferably removable, being attached to the housing by means of a screw thread, bayonet joint, or other suitable form of easily detachable fastening. Cap 3 may be made removable or not, as desired, and carries at its inner side a lamp socket 5, within which a lamp 6 may be screwed and which is provided with a suitable switching mechanism, as for instance, a pull switch operated by the chain 7. A flexible cord 8 provided with a suitable connecting plug is also attached to the socket 5. Both the switch operating means 7 and the flexible cord 8 are brought out from the lamp through the aperture 2.

A cover 9 is hingedly mounted upon the tubular lamp housing 1. We prefer to mount the cover 9 by rolling a wire 10 in the upper edge of the cover and holding the wire 10 in place by means of spring wire loops 11 at each end of the cover 9. Loops 11 pass from the inside of the housing 1, over the wire 10 and into the housing again, and may be conveniently located within beads 12 at each end of the housing. Beads 12 serve to stiffen the housing and also afford a recess for loops 11, so as to present a substantially flat surface on the interior of the housing. The tension of the loops 11 is sufficient to hold the upper edge of the cover 9 in contact with the case and to thus produce sufficient friction to hold the cover 9 in any desired position. The cover 9 may thus be used for a shade, as well as a closure for the opening 2.

Mounted within the housing 1 is a housing supporting means, which may consist of a bracket 13, having a screw ferrule 14 attached thereto by means of a hinge 15. The parts are so proportioned that by swinging the ferrule about the hinge 15, it may be either extended through the aperture, as shown in Figs. 1 and 2, or folded into the body of the lamp housing 1.

The lamp housing is supported by means of a standard 16, which is screwed into ferrule 14 and may be easily removed therefrom. Standard 16 is screwed into one of the base members 17, which in the embodiment illustrated in Fig. 2 consists of a yoke

having a flat foot 18. The base also comprises another base member 19, which is attached to a plunger 20, slidably mounted within the standard 16. The foot or base member 19 is arranged with a raised portion 21, and being pivotally and slidably mounted within the standard 16 may be rotated from a position in alinement with the other foot or base member 18, to a position at right angles thereto, and locked in such angular position. This locking in angular position is facilitated by the engagement of the central portion of foot member 18 with the indented portion 21 of foot member 19.

15 The foot members 18 and 19 are normally held together by means of a spring 22, preferably located within the standard 16. Spring 22 acts against the closed end 23 of the standard 16, or against some other suitable abutment, and against the movable spring abutment 24, which bears against the top of the plunger 20. The length of the plunger 20 is preferably not greater than the diameter of the lamp housing 1, for the purpose of packing the various parts of the lamp, as will be hereinafter explained.

If it is desired to clamp the lamp to a table or other suitable support, the base members are separated against the pressure 30 of the spring 22, and the support inserted between them. It will be noted that because of the raised portion 21 in the foot or base member 19, it is easily possible to attach the lamp upon a rounded surface.

35 When it is desired to pack the lamp, the bulb 6 is first removed, the standard 16 is then unscrewed from the ferrule 14 and the ferrule 14 is folded about the hinge 15 until it comes within the lamp housing 1. Standard 16 is then unscrewed from the base member 17, the removable abutment 24 being prevented from leaving the standard, by means of the turned-in end 25, or other suitable stop. Standard 16 is preferably of a length 40 slightly shorter than the length of the tubular housing and may therefore be easily inserted therein. Foot or base members 18 and 19 are then swung around, so that they come into alinement, and the total height of plunger 20 and the base members being less than the diameter of the tubular housing, and the length of the base members being less than the length of the tubular housing, the two base members and plunger 20 may be inserted into the housing. The switch operating chain 7 and the flexible cord 8 are then put into the housing through the aperture 2, and cover 9 is closed, thus closing housing 1, which then contains all of the parts of the 45 lamp.

Figs. 6, 7 and 8 show a modified form of base, which may be used with the lamp housing and other parts illustrated in Figs. 1 and 2, or with other suitable parts. In this construction, a tension spring 26 is used instead

of the compression spring 22, and the yoke 17 is omitted. As in the embodiment previously described, the standard 16 is tubular, but the plunger 20 is also tubular and of greater length than that shown in the embodiment illustrated in Fig. 2. Standard 16 in the modification illustrated in Figs. 6, 7 and 8 is detachably screwed into foot member 27, and plunger 20 is detachably screwed into foot member 28. Spring 26 is attached at one end to the standard 16, as at 29, and at its opposite end to plunger 20, as at 30. It will thus be seen that the foot or base members 28 may be turned into alinement with one another, as in the modification previously described and that they may be turned to a position at an angle to one another and locked in such position, by means of the engagement of the raised portion 31 of base member 27 with base member 28.

When it is desired to disassemble the standard and base structure of the modification shown in Figs. 6, 7 and 8, foot member 28 is unscrewed from plunger 20 and foot member 27 is unscrewed from standard 16. The motion of plunger 20 in standard 16 may be limited by means of a pin 32, or other suitable stop.

If it is desired to attach the lamp to a table or other support, the foot members are separated against the tension of spring 26 and clamped over the support. In Fig. 8 we have shown a lamp attached to a round supporting member 33, and in order to firmly attach the lamp to rounded supporting members, it is desirable to form foot member 27 with a curved portion 34. If it is desired to attach the lamp to the modification shown in Figs. 6, 7 and 8 to a surface having parallel upper and lower sides, this may be done in the same manner as with the lamp shown in the embodiment of Figs. 1 and 2.

As in the embodiment previously described, the standard 16 is slightly less than the total length of the housing, and the foot members 27 and 28 are also slightly less than such length. They may therefore be inserted in the housing and the lamp packed in the same manner as in the embodiment previously described.

We do not desire to limit ourselves to the particular embodiments illustrated and described, since it is evident that many changes may be made without departing from the spirit of our invention.

What we claim is:

1. An electric lamp, comprising a standard and a base secured thereto, said base including a pair of foot members rotatably mounted with respect to one another and adapted to be rotated into and out of alinement with one another.

2. An electric lamp, comprising a standard and a base secured thereto, said base including a pair of foot members rotatably

mounted with respect to one another and adapted to be rotated into and out of alignment with one another, and spring means for holding the foot members in engagement with one another.

3. An electric lamp, comprising a standard and a base secured thereto, said base including a pair of foot members rotatably mounted with respect to one another, and 10 spring means for holding the foot members in engagement with one another, one of said foot members being offset so that portions thereof will lie in the same horizontal plane as the other foot member, when they 15 are rotated to a position substantially at right angles to one another.

4. An electric lamp, comprising a standard, a foot member secured thereto, a plunger slidably mounted upon the standard, and a second foot member secured thereto and adapted to be rotated into and out of alignment with the first foot member.

5. An electric lamp, comprising a tubular standard, a foot member secured to the 25 lower end thereof, a plunger mounted within the standard, and a second foot member mounted at the lower end thereof and adapted to be rotated into and out of alignment with the first foot member.

30 6. An electric lamp, comprising a tubular standard, a foot member secured to the lower end thereof, a plunger mounted within the standard, a second foot member mounted at the lower end thereof and adapted to be rotated into and out of alignment with the first foot member, and a spring tending to hold said foot members in contact.

7. An electric lamp, comprising a tubular standard, a foot member secured to the 40 lower end thereof, a plunger mounted within the standard, a second foot member mounted at the lower end thereof and adapted to be rotated into and out of alignment with the first foot member, and a 45 spring mounted within the standard, tending to hold said foot members in contact.

8. An electric lamp, comprising a tubular standard, a foot member secured to the lower end thereof, a plunger mounted within 50 the standard, a second foot member mounted at the lower end thereof, means tending to hold said foot members in contact, and means for locking said foot members at an angle to one another.

55 9. An electric lamp, comprising a base having a plurality of portions relatively movable into open and closed positions, a standard detachably secured thereto, a lamp housing having an aperture, and means for 60 securing the lamp housing to the standard, adapted to be folded within the housing through said aperture.

10. An electric lamp, comprising a base, including two foot members adapted to be

rotated with respect to one another and to 65 be moved apart, a standard secured to one of said base members, a lamp housing having an aperture, and means for securing said lamp housing to the standard, adapted to be folded within the housing through said 70 aperture.

11. An electric lamp, comprising a lamp housing, comprising a tubular portion and end portions, one of said end portions being removable, a cover mounted upon the housing and covering an aperture therein, housing supporting means mounted within the housing and adapted to be extended to project through the aperture, a standard secured to the housing supporting means, and 80 a base connected to the standard.

12. An electric lamp, comprising a lamp housing, comprising a tubular portion and end portions, one of said end portions being removable, a cover mounted upon the housing and covering an aperture therein, a lamp socket, provided with switch operating means, adapted to be operated through said aperture, housing supporting means mounted within the housing and adapted to be extended to project through the aperture, a standard secured to the housing supporting means, and a base connected to the standard.

13. An electric lamp, comprising a lamp housing, comprising a tubular portion and 95 end portions, one of said end portions being removable, a cover mounted upon the housing and covering an aperture therein, housing supporting means mounted within the housing and adapted to be extended to project through the aperture, a standard secured to the housing supporting means, and a base connected to the standard, comprising a pair of pivotally mounted members adapted to be rotated to a position at an 100 angle to one another.

14. An electric lamp, comprising a lamp housing, comprising a tubular portion and end portions, one of said end portions being removable, a cover mounted upon the housing and covering an aperture therein, a lamp socket, provided with switch operating means, adapted to be operated through said aperture, housing supporting means mounted within the housing and adapted to be extended to project through the aperture, a standard secured to the housing supporting means, and a base connected to the standard, 110 comprising a pair of base members normally held in contact with one another and rotatable with respect to one another.

15. An electric lamp, comprising a tubular lamp housing having an aperture and end portions, one of which is removable, a cover hinged longitudinally of the housing and adapted to close the aperture, a lamp socket having switch operating means adapted to be operated through said aper-

ture, housing supporting means mounted within the housing and adapted to extend through the aperture, a tubular standard detachably secured to the housing supporting means, a pair of base members, one of which is secured to the standard and the other of which is slidably and pivotally mounted therein, and a spring, tending to hold said

base members in engagement, mounted within the standard.

In testimony whereof, we have signed our names to this specification this 6th day of March, 1918.

F. M. ROSENFELD.
LOUIS E. SHAW.
